[57] CLAIM

The ornamental design for a pump cover, substantially as shown and described.

DESCRIPTION

FIG. 1 is a perspective view of a pump cover showing my new design;

FIG. 2 is a front elevational view thereof;

FIG. 3 is a right side elevational view thereof;

FIG. 4 is a top plan view thereof;

FIG. 5 is a rear elevational view thereof;

FIG. 6 is a bottom plan view thereof; and

FIG. 7 is a left side elevational view thereof.

The broken line representation of a pump in FIG. 1 is for purposes of illustration only.

FIG. 2

FIG. 3
